(57) **CLAIM**

The ornamental design for a storage stand, as shown and described.

DESCRIPTION

FIG. 1 is a perspective view of a storage stand, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the preferred embodiment showing that containers are received in the storage stand, wherein the elements shown in broken lines are for illustrated purpose only and form no part of the invention.
